[57] CLAIM

The ornamental design for an interchangeable one dimensional convergence lens solar radiation intensification plate, substantially as shown and described.

DESCRIPTION

FIG. 1 is a perspective of an interchangeable one dimensional convergence lens solar radiation intensification plate showing my new design.

FIGS. 2, 3, 4, and 5 are perspective views of further embodiments of my new design.

The underside of each embodiment is flat and plain. The plate of each embodiment is understood to have indeterminate length.
